UNITED STATES PATENT OFFICE

124,128

DESIGN FOR A BOAT

Frank R. Greene, Ocala, Fla.

Application April 16, 1940, Serial No. 91,710

Term of patent 3½ years

To all whom it may concern:

Be it known that I, Frank R. Greene, a citizen of the United States and residing at Ocala, in the county of Marion and State of Florida, have invented a new, original, and ornamental Design for a Boat, of which the following is a specification, reference being had to the accompanying drawing, forming part thereof.

I claim:

The ornamental design for a boat, substantially as shown and described.

FRANK R. GREENE,
